UNITED STATES PATENT OFFICE.

JOSEPH BIJUR, OF NEW YORK, N. Y., ASSIGNOR, BY MESNE ASSIGNMENTS, TO BIJUR MOTOR APPLIANCE COMPANY, A CORPORATION OF DELAWARE.

ENGINE STARTING DEVICE.

1,311,854.

Specification of Letters Patent. Patented July 29, 1919.

Application filed July 7, 1914. Serial No. 849,443.

To all whom it may concern:

Be it known that I, JOSEPH BIJUR, a citizen of the United States, residing at New York, in the county of New York and State 5 of New York, have invented certain new and useful Improvements in Engine Starting Devices, of which the following is a full, clear, and exact description, such as will enable others skilled in the art to which it applies to make and use the same.

This invention relates to motors, and with regard to certain more specific features, to a motor adapted to withstand the high speeds encountered in starting devices for 15 internal combustion engines.

One of the objects of the invention is to provide a motor armature of increased efficiency and safety in operation.

Another object is to provide a motor construction in which is secured a path of decreased reluctance for the flux between the fields and the armature core.

Another object is to provide an armature construction wherein the several parts are 25 readily assembled and readily removable, as for inspection and repair.

Another object is to provide engine-starting apparatus of simple and compact construction and so constituted as to obviate 30 the necessity of providing the comparatively cumbersome and expensive protective devices usually needed in such installations.

Another object is to provide a motor whose armature is capable of withstanding with 35 a minimum of danger or depreciation, the extremes of heat, moisture and other deleterious influences encountered in various types of severe service conditions.

Another object is to provide engine-starting apparatus that will operate quietly, efficiently and economically.

Other objects will be in part obvious and in part pointed out hereinafter.

The invention accordingly consists in the 45 features of construction, combinations of elements and arrangement of parts which will be exemplified in the construction hereinafter set forth, and the scope of the application of which will be indicated in the 50 following claims.

In the accompanying drawings, in which are illustrated one or more of various possible embodiments of the several features of the invention,

55 Figure 1 is a longitudinal elevation of a

motor armature showing a preferred type of construction;

Fig. 2 is an enlarged transverse section on the line 2—2 of Fig. 1;

Fig. 3 shows in perspective a type of 60 wedge;

Fig. 4 is a corresponding illustration of a modified wedge construction; and

Fig. 5 is a diagrammatic illustration of a preferred type of engine-starting system 65 embodying several of the features of the present invention.

This invention is a variation of that disclosed in my co-pending application, Serial No. 775,670, filed June 25th, 1913, renewed 70 Nov. 23, 1918, Serial No. 263,947, the matter common to the two applications being included in the claims of the latter application.

Similar reference characters refer to similar parts throughout the several views of the drawings.

Referring now to the drawings, there is illustrated an electric motor 1 whose armature 2 is provided with plates 3, preferably 80 of steel, to retain the conductors 4 in their respective slots 5. Suitable grooves may be provided as at 6, to receive the plates 3 which may be inserted in spaced relation axially along the respective slots 5 if the 85 plates used are of the general type illustrated in Fig. 3, or the plates may comprise a series of spaced portions 7 extending into the grooves 6 and connected to each other by comparatively narrow strips 8. In the 90 former case there would ordinarily be a number of plates for each slot; in the latter, a single plate might well be made long enough to protect the conductors throughout the length of the corresponding slot. 95

It has been found in practice that plates made in accordance with the present invention improve the magnetic path between field and armature, add less to the weight of the armature, detract less from the slot area 100 available for conductors, are less liable to become weakened by heat or moisture, and otherwise contribute to increased efficiency and safety of operation. By providing the plates of magnetic material, there is an increased percentage of peripheral area of the armature available for receiving and transmitting the lines of force passing between the field poles and the armature, in this way improving the magnetic efficiency of the mo- 110

2
tor. The increased fraction of the slot area available for conductors makes it unnecessary to use a slot as deep for a given width as would be the case with retaining devices 5 of other types, and this decrease in the depth of the radial slots increases, of course, the width 9 of the armature teeth 10 at the base of the slots 5 with a resultant increase of magnetic efficiency of the armature. Owing 10 to the comparatively small thickness of the plates 3 they may be placed nearer the top 11 of the armature teeth 10 and the distance 12 between plates is increased for this reason, as well as for the reason that with the 15 construction of the present invention the plates are strong enough so that the grooves retaining them in place may be comparatively shallow.

In order to increase the reluctance of the 20 magnetic circuit across the tops of the slots in the event that the plates are of magnetic material, such as steel, the distances 13 between plates measured axially of the motor may be made as great as is practicable 25 consistent with safety, and in addition the plates of adjoining rows may be relatively staggered, as indicated in Fig. 1. Inasmuch as the construction herein set forth enables extremely high motor speeds to be attained 30 safely without the use of metallic or other banding, the magnetic losses and other disadvantages attendant on the use of such banding, the effective portions of the conductors are avoided. The banding 14 outside 35 the pole pieces and at the commutator serves to hold the rotary parts in place without detracting from the magnetic efficiency of the motor.

The selection of plates of the general type 40 illustrated in Figs. 3 and 4 will depend upon the relative importance of such factors as armature weight, cost of materials and tools, and magnetic leakage on the one hand, and the cost of assembling on the other: Of these 45 four factors, which are cited simply by way of example, an increased efficiency is gained in the first three by the use of plates of the type of Fig. 3. Plates made according to Fig. 4 would be preferred if the fourth factor 50 were controlling.

In applying a motor of the above type for purposes such as the starting of engines inherently incapable of starting themselves, the arrangement of Fig. 5 may be used. 55 Here the motor 1 has a shaft 15 on which is secured a pinion 16 for movement axially of the shaft by means of a manually operated shifting yoke 17 in operative relation with a grooved portion 18 of the pinion. 60 The transmission of power between motor shaft and pinion may be effected by a feather key of any suitable type, or preferably by simply squaring the projecting end of the motor shaft, to register with a square hole 65 in the pinion.

The operation of the device is as follows: assuming the parts in the relative positions indicated at Fig. 5, the engine may be started by depressing actuating member 27, and through it the switch lever 19, to reach 70 the first contact 20, then as the pinion is manually shifted through the yoke 17 into engagement with the toothed gear 21 on the fly-wheel 22, the continued downward movement of the switch lever 19 short-circuits the 75 series starting resistance 23 connecting the motor 1 directly across the battery 24 so that a maximum torque is developed. There should preferably be a mechanical connection as at 25 between the switch lever 19 80 and shifting yoke 17 that will insure a suitable time relation in the operation of these two elements. After engagement has been effected and the full power of the battery delivered to the motor the fly-wheel will 85 ordinarily be set in motion and the engine will begin to rotate under its own power. When this occurs it is expected that the operator will allow the spring 26 to return the pinion and switch-handle to their 90 former positions of disengagement and open-circuit respectively. In case he fails to do so, the comparatively high speed of the fly-wheel would cause the motor to rotate at a speed of the magnitude of hundreds of revolutions per second, but the motor construction, illustrated in Figs. 1 to 4 and described above, is such that this high speed does no harm to the motor. It will thus be seen that the combination of features herein set 95 forth obviates the necessity of protecting the motor by automatic mechanism from this high speed occasioned by the operator's failure to release the pedal 27 promptly. With the present invention, therefore, there is no 100 need of apparatus such as roller clutches, sliding armatures, centrifugal cut-outs or other devices, which no matter how efficient or economical *per se*, nevertheless add something to the uncertainty of operation or the 105 efficiency, or cost, or noise, or the space required for such automatic devices and the difficulties of installation occasioned by their use.

As many changes could be made in the 115 above construction and many apparently widely different embodiments of this invention could be made without departing from the scope thereof, it is intended that all matter contained in the above description 120 or shown in the accompanying drawings shall be interpreted as illustrative and not in a limiting sense.

Having described my invention, what I claim as new and desire to secure by Letters 125 Patent is:—

1. In a motor vehicle, the combination with an internal combustion engine, an electric starting motor, a battery, a resistance, a unitary switch contact, connecting means 130

for said motor and engine; and a single actuating member for successively operating said contact to start said motor with the resistance in circuit, for moving said connecting means into operation, and for moving said contact to cut out said resistance.

2. In a motor vehicle, the combination with an internal combustion engine, an electric starting motor, a battery, a resistance, a unitary switch contact, connecting means for said motor and engine, and a single actuating member for successively operating said contact to start said motor with the resistance in circuit, for moving said connecting means into operation, and for moving said contact to bridge and short-circuit said resistance.

3. In a motor vehicle, the combination

with an internal combustion engine, an electric starting motor therefor, movable connecting means for said motor and engine, a source of current and connections for operating said motor, and means including a single actuating member, a pivoted member rigidly connected thereto at its pivot, for operating on said connections to start the motor, for moving said connecting means into operation, and afterward operating on said connections to give the motor a working energy for starting the engine.

In testimony whereof I affix my signature, in the presence of two witnesses.

JOSEPH BIJUR
